UNITED STATES PATENT OFFICE.

CHARLES HERBERT FARNSWORTH, OF BRICELAND, CALIFORNIA.

SET-TRIGGER FIREARM.

1,102,026.

Specification of Letters Patent. Patented June 30, 1914.

Application filed June 19, 1912. Serial No. 704,614.

To all whom it may concern:

Be it known that I, CHARLES H. FARNSWORTH, a citizen of the United States, residing at Briceland, in the county of Humboldt and State of California, have invented 5 new and useful Improvements in Set-Trigger Firearms, of which the following is a specification.

In small firearms of the nature embodying 10 a set trigger many movements are usually required for operating the set trigger so that the gun may be fired by a comparatively light pressure of the finger without disturbing the accuracy of aim when the 15 gun is pointed at a mark.

The present invention provides a firearm which admits of the trigger being automatically set by means of the hammer when cocking the gun.

20 The invention provides the hammer with a pin of such relative proportions and arrangement as to engage the head of the set trigger upon moving the hammer backward a short distance after being brought to full 25 cock so that a light pressure upon the set trigger will release the hammer and fire the gun.

The invention consists of the novel features, details of construction and combination of parts, which hereinafter will be 30 more particularly set forth, illustrated in the accompanying drawing, and pointed out in the appended claim.

Referring to the drawings, forming a part 35 of the specification, Figure 1 is a side view of the lock mechanism of a firearm embodying the invention, parts being broken away and the different elements being in the position which they occupy when the hammer is 40 thrown forward. Fig. 2 is a view of the parts illustrated in Fig. 1, showing the relation of the elements when the hammer is at full cock. Fig. 3 is a side view of the lock mechanism removed from the stock, the 45 same being reversed and partly in section, the hammer being thrown forward. Fig. 4 is a view of the parts shown in Fig. 3, the hammer being drawn backward to half cock. Fig. 5 is a view similar to Fig. 4 with the 50 hammer drawn backward beyond a full cock position so as to automatically set the trigger. Fig. 6 is a cross section on the line 6-6 of Fig. 3.

Corresponding and like parts are referred 55 to in the following description, and indi-

cated in all the views of the drawing, by the same reference characters.

The numeral 1 designates the stock of a small firearm, such as a rifle or shotgun, and 60 2 indicates the barrel thereof. The stock is recessed in the accustomed way to receive the lock mechanism, the latter comprising a frame 3 to which the operating parts of the firing mechanism are attached. The hammer 4 is pivoted between ears of the frame 65 upon a pin 5. The main spring 6 is connected with the frame and hammer in the usual way. The sear 7 is mounted upon a pin 8 and is of ordinary construction and is adapted to engage the notches in the butt 70 of the hammer to hold the same at half or full cock in the manner well understood. The sear spring 9 engages a toe of the sear. The main trigger 10 is mounted upon the pin 8 and has a finger 11 and a lug 12. A 75 spring 13 is adapted to engage the finger 11 to exert a downward pressure thereon to throw the trigger 10 forwardly and the lug 12 rearwardly. The set trigger 14 has a head 15 which is adapted to engage a 80 shoulder near the forward end of the sear 7. The head 15 is mounted upon a pin 16 and has a slot 17 which receives a pin 18 extending inwardly from a side of the frame 3, thereby limiting the movements of the set 85 trigger. A lug 19 projecting laterally from the rear portion of the head 15 is adapted to engage under the lug 12 of the trigger 10 when the gun is set to be fired by pressure upon the trigger 10. The rear portion of the head 15 is adapted to be engaged by a pin 20 carried by the hammer 4 so as to depress the rear portion of the head 15 and set the trigger 14 upon drawing the 90 hammer 4 backwardly after being brought to full cock. A spring 21 is adapted to engage the rear portion of the head 15 and exert an upward pressure thereon to hold the lug 19 clear of the space under the lug 12, thereby preventing a setting of the trigger 95 14 except by a rearward movement of the hammer after the same has been brought to full cock. 100

When the hammer is thrown forward so as to fire the gun the parts occupy the relative positions shown in Figs. 1 and 3 and when the hammer is drawn backward into full cock the parts occupy the relative positions indicated in Fig. 2. To set the trigger 110 14 the hammer is pressed rearwardly after

being brought to full cock, as indicated in Fig. 5, thereby bringing the lug 19 in position below the lug 12 which engages therewith and permits the trigger 10 to move forwardly so that a light pressure upon the trigger 10 will fire the gun. A fly 22 is pivoted to a side of the butt of the hammer and is adapted to cover the half cock notch to prevent the sear catching thereon when 5
 10 the hammer is released by pressure upon the trigger after said hammer has been brought to a position of full cock. It is observed that the trigger may be set automatically by means of the hammer when the 15 same is drawn backward into firing position. When it is not required to set the trigger the hammer is drawn backwardly to full cock only, thereby preventing premature firing of the gun by accidental pressure upon 20 the trigger 10 by means of a twig or other object.

From the foregoing description, taken in connection with the accompanying drawing, the advantages of the construction and of 25 the method of operation will be readily apparent to those skilled in the art to which the invention appertains, and while I have described the principle of operation of the invention, together with the device which I 30 now consider to be the best embodiment

thereof, I desire to have it understood that the device shown is merely illustrative, and that such changes may be made when desired as are within the scope of the claim appended hereto. 35

Having thus described the invention what is claimed as new, is:—

In a set trigger firearm, the combination of a hammer, a sear therefor, a main trigger having a head adapted to engage the sear to trip the same, resilient means for normally maintaining the said trigger in a position with its head in engagement with the sear, a laterally extending lug formed upon said main trigger, a set trigger having a longitudinal lug for coöperation with the lug of the main trigger, and means carried by the hammer for engagement with the head of the main trigger to depress the same against the action of the said resilient means upon moving the hammer backwardly from its full cocked position to enable the main trigger lug to engage beneath the lug of the set trigger. 40
